PROCESS FOR THE IMPROVEMENT OF KNOCK RATING OF GASOLINE

Filed June 6, 1938

UNITED STATES PATENT OFFICE

2,263,026

PROCESS FOR THE IMPROVEMENT OF
KNOCK RATING OF GASOLINEMaurice H. Arveson, Flossmoor, Ill., assignor to
Standard Oil Company, Chicago, Ill., a corpora-
tion of Indiana

Application June 6, 1938, Serial No. 212,008

14 Claims. (Cl. 196—49)

This invention relates to the conversion of hydrocarbons and particularly to the conversion of low knock rating gasoline into gasoline of high knock rating by treatment with catalysts. More particularly, the process relates to the treatment of straight run, substantially saturated gasolines and naphthas to convert them into a gasoline having a high anti-detonating value. One object of the process is to convert low knock rating motor fuels into high knock rating motor fuels with a minimum loss of motor fuel in the process. Another object of the process is to effect the conversion of low knock rating motor fuels into high knock rating motor fuels with a minimum heat requirement and at temperatures considerably lower than those heretofore used. The invention is illustrated by a drawing which is a flow diagram showing the various steps of the process.

Heretofore it has been common practice to convert low knock rating gasolines and naphthas to high knock rating gasolines by subjecting them to the reforming process. In that process, the oil, for example, straight run heavy naphtha, is heated to a high temperature, e. g. 950 to 1100° F., and cracked sufficiently to produce a gasoline usually having a knock rating of about 72 to 75 octane number from a heavy naphtha having a knock rating of about 35 to 55 octane number. In such an operation the gasoline loss usually has amounted to 15 to 25%, the loss consisting mainly of fuel gases, tar and coke. An important object of my process is to direct the conversion of the knock inducing paraffinic hydrocarbons into high knock rating gasoline so as to produce a minimum of byproduct gases, coke, etc. By my process the paraffinic hydrocarbons are transformed or isomerized into aromatic hydrocarbons, branched chain olefines and some naphthenic hydrocarbons which have high knock preventing properties when employed in gasoline engine fuel.

Referring to the drawing, a suitable charging stock, for example straight run heavy naphtha of 10 to 55 octane number from supply tank 10 is introduced by pump 11 and line 12 to coil 13 in heater 14. The oil is vaporized and heated to a temperature of 750 to 900° F. The hot vapors are conducted by line 15 to one of the catalyst chambers 16, two or more chambers being provided for alternate regeneration hereinafter described. Chambers 16 are charged with a suitable dehydrogenation catalyst in granular or pelleted form, allowing free passage of the hot hydrocarbon vapors therethrough. Various types of catalyst may be employed for effecting the desired dehydrogenation such as chromium oxide, chromium oxide gel, metal chromites, etc., such as those described in patent applications Serial No. 180,301 filed December 17, 1937, Serial No.

180,302, filed December 17, 1937, now U. S. Patent 2,205,140, and Serial No. 182,855 filed December 31, 1937, now U. S. Patent 2,205,141. For example, I may use magnesium chromite, Guignet's green, molybdenum oxides, etc., and I prefer to use a catalyst of the chromium oxide type. For example, chromium hydroxide may be precipitated from its salts by a suitable alkali, e. g., ammonium hydroxide, thus producing a chromium oxide gel which, after careful washing and drying, may be dehydrated and graded to the desired form. Various modifying agents and promoters may be incorporated in the chromium hydroxide to assist its dehydrogenating action and increase the active life. As an example of such a catalyst, I may use two mols chromium hydroxide combined with one mol of zinc hydroxide and sufficient barium chloride to amount to 5% of the weight of zinc hydroxide employed.

10 The hot vapors in traversing catalyst chambers 16 are extensively dehydrogenated with the production of olefin hydrocarbons and some aromatic hydrocarbons and the products are led by line 17 and line 18 to isomerization chambers 19. Like chambers 16, chambers 19 are also provided in multiple in order that one or more chambers may be operating while other chambers are being regenerated. In chambers 19 I employ a suitable isomerizing catalyst such as alumina, preferably mounted on silica gel, Kieselguhr or pumice. 15 I may also employ porous forms of carbon, for example, activated charcoal impregnated with phosphoric acid. Phosphoric acid may also be employed on Kieselguhr. The temperature employed in chambers 19 will usually be lower for example, 600-750° F., than the temperature employed in chambers 16 although with different catalysts, I may employ the same temperature i. e., about 750 to 900° F. or even a somewhat higher temperature i. e., about 900 to 1050° F., by bypassing a portion of the vapors from line 17, valve line 20, heating coil 21 and thence through line 22 in the order named.

In traversing catalyst chambers 19 the unsaturated paraffin hydrocarbons are largely rearranged by the catalyst into branched chain and cyclic hydrocarbons. Hydrogen present from the dehydrogenation in chambers 16 likewise assists in reducing the formation of carbonaceous matter and tar, permitting the isomerizing catalyst in chambers 19 to be operated at a higher temperature than would otherwise be practicable.

In carrying out the isomerization of the products of dehydrogenation in chambers 19, it is sometimes desirable to add thereto controlled amounts of water vapor. This may be done in one of two ways—first, addition of steam by line 17a to the stream in line 17 wherein it may be passed with the stream directly to the isomerization chambers from chambers 16, or be by-passed

with hydrocarbon through line 20 to heating coil 21 through line 22 and line 18 to isomerization chambers 19. The second procedure is to pass the hydrocarbon through lines 17 and 18 directly to isomerization chambers 19 and introduce steam by line 20a into line 20 and heating coil 21, thence by line 22 to join the hydrocarbon stream in line 18. By thus superheating the steam, the reduction in temperature of the hydrocarbon in line 18 by the addition thereof can be avoided while the temperature in line 18 can be raised without heating the hydrocarbons directly.

The quantities of steam will vary, depending on the type of catalyst, the nature of the feed stock, but the following general direction can be given: For every mol of liquid feed passing through pump 11, .05 to 1 mol of water may be added as steam through line 17a.

The vapors leaving chambers 19 are conducted by line 23 to fractionator 24 where they are separated into an unvaporized heavy oil fraction which is withdrawn by line 25 and a gasoline fraction which is withdrawn by vapor line 26. Heat for fractionation may be supplied by heater 27. Distillate vapors in line 26 are condensed by condenser 28 and separated in drum 29 whence the uncondensed gases are withdrawn by line 30 and the liquid products are removed by line 31 and pump 32 which returns a portion thereof by line 33 to the upper part of fractionator 24 as a reflux. The remaining gasoline fraction is conducted by line 35 to stabilizing tower 36 heated by heater 37. The vapors are withdrawn from the upper part of fractionator 36 by line 38 and partially condensed in condenser 39. The condensate and uncondensed gases are separated in drum 40 and discharged by line 41 while the liquid products, consisting mainly of liquid propane with some butane and ethane, are withdrawn by line 42 and pump 43. A portion of the condensate is returned by line 44 to tower 36 as reflux, the remaining liquid products being discharged by line 45. Gasoline is withdrawn from the base of stabilizer tower 36 by valved line 46 and may be given suitable chemical treatment such as stabilization against gum formation by the addition of antioxidants, etc.

Depending on the circumstances under which this process is used, it may be economically desirable to separate the gasoline obtained from line 46 into converted and unconverted fractions and recycle the unconverted fractions with the original feed. The unconverted fractions may be introduced into tank 10 through line 49. Various means may be used for separating the gasoline, but the most practical method is that of solvent extraction using selective solvents. The quantities, temperatures and types of solvents will vary with the circumstances and the following method is given by way of illustration. The gasoline from line 46 may be extracted in a countercurrent extraction apparatus using liquid SO_2 at a temperature around 90° F., the quantity of solvent being about 1 to 1½ volumes per volume of gasoline fed. The raffinate and extract layers are removed and distilled to remove solvent, the extract being the desired finished product consisting mostly of branched chain olefins, aromatics and some naphthenes. The raffinate being predominantly paraffinic, is returned to the dehydrogenation and isomerization process for further processing.

In the case where highly paraffinic, low knock rating feed stocks are not available, as such, in

the refinery, products of higher knock rating, e. g., cracked heavy naphtha may be introduced into the solvent extraction step described, and the raffinate thus obtained may be employed as feed stock in tank 10 for carrying out the process.

Another method of separation which may be used involves azeotropic distillation with various polar substances such as liquid SO_2 , acetic acid, etc. When a process such as azeotropic distillation is to be used for separation, it is highly desirable that the feed through the process be a comparatively narrow cut. It is not necessary that the cut sent to the process be of a fixed distillation range throughout the run or runs, but it is important that at any one instant the feed stock be of narrow boiling range, so that on azeotropic distillation a satisfactory separation can be made. For example, a wide boiling range heavy naphtha may be distilled in a batch-wise operation and the distillate as obtained run immediately to the process. A naphtha stream of continually changing boiling range is thus obtained but at any given time it has a narrow boiling range suitable for separation by azeotropic distillation. The paraffinic fraction so obtained is suitable as charging stock for my process.

The gasoline produced in my process will ordinarily have a knock rating of about 70 to 80 octane number, although higher knock ratings may be obtained by more extensive dehydrogenation and isomerization in chambers 16 and 19. This may be accomplished by reducing the rate of flow of vapors therethrough and/or increasing the temperature of the treatment. However, if the temperature employed in chambers 16 and 19 is too high cracking will result and rapid fouling of the catalyst will take place, thus requiring regeneration at more frequent intervals.

When the catalyst in one of the chambers 16 becomes sufficiently inactive to prevent its continued use at an economical rate it may be regenerated by diverting the flow of vapors to a fresh catalyst chamber by means of the valves shown and then sweeping the hydrocarbon vapors from the catalyst chamber with a suitable inert gas, e. g., flue gas or steam. For this purpose lines 47 and 48 are employed. After the vapors are swept from the chamber an oxidizing gas is introduced into the catalyst chamber for the purpose of burning out carbonaceous matter deposited on the catalyst. Air may be used for this purpose, preferably diluted with flue gas or other inert diluent to regulate the rate of combustion and avoid excessive temperature rise. In general the temperature is regulated by the oxygen concentration during the regeneration cycle to avoid heating the catalyst to temperatures above 1000° F. as it has been found that higher temperatures than this result in a permanent deterioration of the catalyst. This result may be attained by beginning regeneration with flue gas mixed with sufficient air to produce an oxygen concentration of about 0.2%, after which the oxygen concentration may be gradually increased as the extent of regeneration progresses. Thermocouples distributed throughout the catalyst mass serve to indicate the progress of the regeneration.

After regeneration the catalyst may be used again and again, the regeneration being repeated until the efficiency falls below an economical point. It is not necessary to regenerate the catalyst simultaneously in the dehydrogenation zone

and the isomerization zone, the life of the catalyst in the two zones being different. After repeated regeneration, when the catalyst is deteriorated to a point where it is no longer economical to regenerate it further, it may be renewed and the spent catalyst may be processed to recover valuable ingredients. The total life of the isomerization and dehydrogenation catalysts are usually considerably different, the isomerization catalyst usually having the shorter life and requiring more frequent renewal. In the case of the phosphoric acid type isomerizing catalyst a portion of the acid may be lost at each regeneration cycle which tends to reduce the total life of the catalyst more rapidly than in the case of the chromium oxide dehydrogenation catalysts.

The pressures employed in my process are preferably low. For example, I may employ atmospheric pressure in both the dehydrogenation and isomerization stages. The pressure in both stages is approximately the same and in fact I may combine the dehydrogenating and isomerizing catalysts in a single reaction chamber. I prefer to employ moderate pressures in my process, e. g., 10 to 50 pounds per square inch. However, higher pressures may be used, e. g., 200 to 300 pounds per square inch. Although I have described conducting the dehydrogenating and isomerizing process under conditions which produce more extensive decomposition of the naphtha than simple dehydrogenation, I prefer to regulate the temperature and time of treating in the catalyst zones to limit the action substantially to dehydrogenation thereby producing a treated high knock rating heavy naphtha having approximately the same boiling characteristics as the naphtha charged to the process thereby avoiding loss of motor fuel by production of fixed gases and undesirable light hydrocarbons.

Although I have described my process in connection with certain specific embodiments thereof I intend that the scope of my invention be limited only by the following claims.

I claim:

1. The process of converting low knock rating paraffinic gasoline into high knock rating aromatic gasoline which comprises subjecting the vapors of said paraffinic gasoline to the action of a dehydrogenation catalyst in a first catalyst zone at a temperature of about 750 to 900° F. whereby paraffin hydrocarbons are converted to olefins and hydrogen, then conducting the combined vapors while still hot through a second catalyst zone in contact with an isomerizing catalyst different from the said dehydrogenation catalyst whereby the said olefin hydrocarbons are rearranged and thereafter separating a gasoline motor fuel from the products of said reaction.

2. The process of claim 1 wherein the dehydrogenation catalyst contains an oxide of chromium.

3. The process of claim 1 wherein the said isomerization catalyst is comprised of phosphoric acid.

4. The process of claim 1 wherein the temperature employed in the isomerizing catalyst zone is substantially the same as the temperature employed in the dehydrogenating catalyst zone.

5. The process of claim 1 wherein the low knock rating gasoline treated is a straight run heavy naphtha fraction having an octane number between about 10 and 55.

6. The process of claim 1 wherein said isomerization catalyst is comprised of aluminum oxide.

7. The process of converting paraffinic naphtha of low knock rating into high knock rating gasoline containing substantial amounts of aromatic hydrocarbons, which comprises vaporizing and heating said naphtha to conversion temperature, conducting a stream of the vapors through a porous bed of a dehydrogenating catalyst under dehydrogenating conditions at an elevated conversion temperature and at a rate sufficient to convert a substantial amount of said paraffinic naphtha to olefine hydrocarbons and hydrogen, conducting the resulting mixture of hydrocarbons and hydrogen through a second porous bed of an isomerizing catalyst different from said dehydrogenating catalyst at a high temperature and substantially without condensation of said hydrocarbons whereby said olefines are substantially converted into aromatic, naphthenic and branched chain olefinic hydrocarbons in the presence of said hydrogen and whereby said hydrogen reduces the tendency of carbonaceous deposits to form on said catalyst, withdrawing the reaction products from said isomerizing catalyst and separating high knock rating gasoline therefrom by fractional distillation.

8. The process of claim 7 wherein the catalytic reactions are conducted at a pressure of about 10 to 50 lbs. per square inch.

9. The process of claim 7 wherein the products of the dehydrogenation reaction are further heated before subjecting to said isomerizing catalyst.

10. The process of claim 7 wherein the said dehydrogenation catalyst is selected from the class consisting of compounds of chromium and molybdenum.

11. The process of claim 7 wherein the said dehydrogenation catalyst is selected from the class consisting of compounds of chromium and molybdenum and said isomerizing catalyst is alumina.

12. The process of claim 7 wherein water vapor is added to said mixture of hydrocarbon vapors and hydrogen before subjecting to said isomerizing catalyst.

13. The process of converting low knock rating paraffinic gasoline into high knock rating gasoline which comprises vaporizing said gasoline and subjecting the vapors thereof, under dehydrogenation conditions, to the action of a dehydrogenation catalyst in a first catalyst zone, whereby paraffinic hydrocarbons are converted to olefins and hydrogen, conducting the resulting vapors of hydrocarbons and hydrogen substantially without condensation through a second catalyst zone, in contact with an isomerization catalyst different from said dehydrogenation

catalyst maintaining in said second catalyst zone of isomerization a different temperature from the temperature of dehydrogenation maintained in said first catalyst zone, thereby effecting isomerization of said olefin hydrocarbons and withdrawing the desired gasoline from said second catalyst zone.

14. The process of claim 13 wherein the catalyst employed in said dehydrogenation zone is a compound selected from the class consisting of chromium oxide and molybdenum oxide and the catalyst employed in said second catalyst zone is alumina.

MAURICE H. ARVESON.
